FOREIGN PATENT DOCUMENTS

GB 2470188 11/2010

Primary Examiner — Sheryl Lane*Assistant Examiner* — Aula Soroush(74) *Attorney, Agent, or Firm* — Neal, Gerber & Eisenberg LLP(57) **CLAIM**

The ornamental design for an inhalant dispenser, as shown and described.

DESCRIPTION

FIG. 1 is a perspective view of an inhalant dispenser.

FIG. 2 is a front view of the inhalant dispenser shown in FIG. 1.

FIG. 3 is a rear view of the inhalant dispenser shown in FIG. 1, opposite the front view shown in FIG. 2.

FIG. 4 is a side view of the inhalant dispenser shown in FIG. 1.

FIG. 5 is a side view of the inhalant dispenser shown in FIG. 1, opposite of the side shown in FIG. 4.

FIG. 6 is a top view of the inhalant dispenser shown in FIG. 1.

FIG. 7 is a bottom view of the inhalant dispenser shown in FIG. 1, opposite the top view shown in FIG. 6; and, FIG. 8 is a partially exploded view of the inhalant dispenser shown in FIG. 1.

The dot-dash broken lines represent the bounds of the claimed design while all other broken lines represent environmental subject matter; the broken lines form no part of the claimed design.

1 Claim, 6 Drawing Sheets(56)
